DESIGN FOR A TIRE-TREAD.

58,984.

Specification for Design.

Patented Sept. 6, 1921.

Application filed October 16, 1920. Serial No. 417,496. Term of patent 7 years.

To all whom it may concern:

Be it known that I, HELEN S. Yost, a citizen of the United States, residing at Batavia, in the county of Genesee and State of New York, have invented a new, original, and ornamental Design for Tire-Treads, of which the following is a specification, reference being had to the accompanying drawing, forming a part thereof.

In the accompanying drawings:

Figure 1 is a face view of a portion of a tire having a tread embodying my new design.

Fig. 2 is a transverse sectional view thereof on line 2—2, Fig. 1.

I claim:

The ornamental design for a tire tread, substantially as shown.
